UNITED STATES PATENT OFFICE

2,372,915

SCREEN

Emerson D. Todd, Detroit, Mich.

Application September 14, 1943, Serial No. 502,332

3 Claims. (Cl. 160—381)

This invention relates to window screens and has for the primary object, the provision of a screen construction which will be extremely durable, and may be economically manufactured and sold in a knock-down condition, easily assembled and made to fit window frames of different sizes by a layman.

Another object of this invention is the provision of a metallic frame wherein the rails thereof may be stamped from sheet metal and each rail includes companion sections ribbed and grooved to interlock when assembled and provide means of clamping the foraminous material of the screen thereto as well as providing rigidity to the screen frame.

A further object of this invention is the provision of corner brackets interlocking with the sections of the rails for securing the sections of the rails to the frame formation and cooperating with the rails in providing a frame which will have a maximum amount of rigidity to prevent distortion or sagging out of shape of the frame when in use.

With these and other objects in view as will become more apparent as the description proceeds, the invention consists of certain novel features of construction, combination and arrangement of parts as will be more fully hereinafter described and claimed.

For a complete understanding of my invention, reference is to be had to the following description and accompanying drawing in which—

Figure 1 is a front elevation illustrating a screen constructed in accordance with my invention.

Figure 2 is a fragmentary transverse sectional view taken on the line 2—2 of Figure 1.

Figure 3 is a fragmentary perspective view illustrating one of the sections of one of the rails of the screen frame.

Figure 4 is a perspective view illustrating one of the corner brackets.

Referring in detail to the drawing, the numeral 5 indicates the frame and 6 the foraminous material. The frame 5 includes longitudinal and vertical rails and corner brackets 7. Each rail includes companion sections 8 and each section and each bracket is preferably stamped from sheet metal and have pressed therein ribs 9 providing grooves 10. The ribs provide the necessary rigidity to the sheet metal. The sheet metal of each section and each bracket is bent at right angles to form a flange 11. Further the sheet metal of each section and each bracket is provided with openings 12 for the purpose of receiving any suit-

able type of fasteners for securing together of the sections of the rails and brackets to the rails and to permit the complete disassembling of the rails when desired.

5 It is proposed that the rail sections be constructed in a length that will permit the purchaser to cut them in proper lengths for the frame to fit a particular size of window when the frame is assembled.

10 The companion sections of the rails in assembling the frame has the screen material 6 arranged therebetween so that when the sections are brought together the foraminous material will be forced into the grooves by the ribs of one section fitting in the grooves of the companion section. Thus when the sections are secured together by the fasteners the foraminous material is firmly anchored in the frame 5. The grooves 10 of the corner brackets receive the ribs of the 15 rails so that the flanges of the corner brackets abut the flanges of the rails and are arranged inwardly thereof.

Thus it will be seen that when the rails and brackets are assembled in frame formation and secured by the fasteners a very rigid and durable frame is provided, one which will not sag or become out of shape and also will not permit the foraminous material to become loose. If the frame is of the sliding type in the window frame 20 the flanges of the rails will provide comparatively broad surfaces to engage with the window frame and permit the screen frame to slide freely and is of the swinging type the flanges of the rails may be employed for attaching the hinges to the screen frame. Further it will be seen that a screen of 25 the construction described and shown in the drawing can be economically manufactured in that all the elements of the frame may be formed from sheet metal and then cut by any layman to 30 assemble the frame of a desired size. It is to be understood that the frame 5 may be used in conjunction with foraminous material either of metallic or plastic nature.

45 While I have shown and described the preferred embodiment of my invention, it is to be understood that minor changes in construction, combination and arrangement of parts may be made without departing from the spirit and scope of the invention as claimed.

50 Having thus described my invention, what I claim is:

1. In a screen, a frame including vertical and longitudinal rails and corner brackets bracing said rails at the corners of the frame, said rails 55 each including companion sections, foraminous

material closing the frame and extending between and gripped by said sections, and means for securing the companion sections together and the brackets to the rails, and flanges formed on the outer edges of each section of the rails and extending outwardly from the respective sides of the frame to provide abutments at the corners and at each side of the frame for selectively positioning the corner brackets at either or both sides of the frame.

2. In a screen, a frame including vertical and longitudinal rails and corner brackets for bracing said rails at the corners of the frame, said rails each including companion sections, said sections and brackets struck from sheet metal material and each provided with ribs defining grooves, foraminous material closing the frame and extending between the sections of the rails and forced into the grooves by the ribs, fasteners securing the companion sections together and the brackets to the rails, and flanges formed on the outer edges of each section of the rails and extending outwardly

from the respective sides of the frame to provide abutments at the corners and at each side of the frame for selectively positioning the corner brackets at either or both sides of the frame.

- 5 3. In a screen, a frame including vertical and longitudinal rails and corner brackets for bracing said rails at the corners of the frame, said rails each including companion sections, said sections and brackets struck from sheet metal material and each provided with ribs defining grooves, foraminous material closing the frame and extending between the sections of the rails and forced into the grooves by the ribs, fasteners securing the companion sections together and the brackets to the rails, a flange formed on the outer edge of each section and extending at right angles thereto, and flanges formed at right angles on the outer edges of the corner bracket and positioned against the flanges of adjoining sections at either or both sides of the frame when the sections are assembled in frame formation.

EMERSON D. TODD.
